UNITED STATES PATENT OFFICE.

JOHN E. HENRIS, OF FOLSOM CITY, CALIFORNIA.

GATE.

1,241,972.

Specification of Letters Patent.

Patented Oct. 2, 1917.

Application filed May 17, 1916. Serial No. 98,141.

To all whom it may concern:

Be it known that I, JOHN E. HENRIS, a citizen of the United States, residing at Folsom City, in the county of Sacramento and State of California, have invented new and useful Improvements in Gates, of which the following is a specification.

This invention relates to gates and particularly to that class of gates which are 10 adapted to be operated by a person seated in a vehicle without necessity of dismounting.

The invention further relates to that class of gates which are supported by tilttable bars 15 or levers for swinging movement in a vertical plane through an arc, the gate being thus opened or closed according to the direction of movement.

The present invention has for its object 20 to simplify and improve the construction of the gate and its supporting and operating means.

A further object of the invention is to produce a simple and improved latch adapted 25 to engage the heel of the gate for the purpose of securing the same against movement when closed.

A further object of the invention is to produce an improved construction whereby 30 the latch will be actuated simultaneously with the gate actuating means.

With these and other ends in view which will readily appear as the nature of the invention is better understood, the same consists 35 in the improved construction and novel arrangement and combination of parts which will be hereinafter fully described and particularly pointed out in the claims.

In the accompanying drawings has been 40 illustrated a simple and preferred form of the invention, it being, however, understood that no limitation is necessarily made to the precise structural details therein exhibited, but that changes, alterations and modifications within the scope of the claims may be resorted to when desired.

In the drawings,

Figure 1 is a view in side elevation showing the gate closed, dotted lines being used 50 to show the gate at an early stage of its opening movement.

Fig. 2 is a side elevation showing the gate open.

Fig. 3 is a vertical transverse sectional 55 view taken on the line 3—3 in Fig. 1.

Fig. 4 is a top plan view showing the gate closed.

Fig. 5 is a transverse sectional view taken on the line 5—5 in Fig. 2.

Fig. 6 is a detail view showing the relative positions of the latch and the heel of the gate when the gate is moving in the direction of its closed position and has almost completed its movement.

Corresponding parts in the several figures 65 are denoted by like characters of reference.

The improved gate structure includes two uprights 15 that are connected together near their upper ends by a cross bar 16. Levers 17 whereby the gate is operated are fulcrumed on said bar. The lower ends of the uprights 15 are connected with the ends of a pair of sills 18 which constitute the base or support of the device and which may be embedded or partly embedded in the ground. 70

The gate panel G may be of any suitable construction; in the drawing it has been shown as being composed of a plurality of horizontal planks 19 that are spaced apart and connected together by the vertically disposed cleats 20, 21, 22; the cleats 20 and 22 being located, respectively, at the front and rear ends of the gate panel and the cleats 21 near the middle portion thereof. It is, however, to be understood that the construction 85 of the gate panel may be greatly varied without departing from the spirit of the invention. Supported on the sills 18 and extending between the lower ends of the uprights 15 is a rock shaft 23 having arms 24, 90

24', one of which is pivotally connected with the upper ends of the middle cleats 21 of the gate panel, which latter will thus be swingingly supported. A second rock shaft 25 which is supported on the sills a suitable 95 distance from the first mentioned rock shaft has an arm 26 which is pivotally connected with the upper ends of the cleats 22 at the rear end of the gate panel, which latter will thus be balanced and steadied. It will be 100 seen that the gate may be opened or closed by swinging it between the uprights 15 from one side of said uprights to the other. To produce this swinging movement the arms 24, 24' of the rock shaft 23 are connected 105 by flexible elements 27, 27' with the levers 17 at what may be regarded as the inner ends of said levers.

It follows that by depressing the outer ends or arms of said levers the arms 24, 24' will be rocked, thereby 110

lifting the gate and swinging it between the uprights 15 from its open to its closed position, or vice versa, the arm 26 of the rock shaft 25 serving to raise the gate and 5 to steady the movement thereof.

Supported on the sills 18 intermediate the rock shafts 23 and 25, and relatively near the first mentioned of said rock shafts which, as hereinbefore stated, extends between the 10 lower ends of the uprights 15 is a third rock shaft 28 having arms 29 that extend in the direction of the rock shaft 25, said arms being preferably weighted, as indicated at 30, so that they will normally rest on the 15 sills. Formed on the rock shaft 28 is a yoke or crank 31 which is bent upward with respect to the arms 29 so as to lie in an inclined plane when the arms 29 rest on the sills. This device constitutes a locking 20 vice or latch for the gate, it being so proportioned and arranged that the yoke or crank 31, when the gate is closed, as in Fig. 1, will lie adjacent to and in the path of the heel portion of said gate, the heel consisting 25 of the corner portion at the lower end of the cleat 22. The parts are to be, furthermore, so proportioned that if the gate should be moved in an opening direction by actuating one of the levers 17 to swing the arms 24, 30 24', the lifting movement of the gate caused thereby will not be sufficient to clear the yoke or crank 31, the latter thus forming an obstruction to the opening of the gate.

For the purpose of moving the latch device 35 vice to a non-obstructing position, flexible elements, such as cords 32, are employed, said elements being connected with the ends of the arms 29 and guided through eyes 33 on the arms 24, 24'. The flexible elements 40 32 are also guided through the eyes or guide elements 34 at the outer ends of the levers 17 from which the said flexible elements are permitted to depend, as shown, being preferably provided with knobs or 45 handles 35 whereby they may be conveniently seized for the purpose of pulling the same.

A stop member 36 is provided to limit the swinging movement of the latch device. 50 Said stop member may be in the nature of a cross piece extending between the sills 18 and lying in the path of the crank or yoke 31, the object being to interrupt the movement of the latch device when the latter has 55 been rocked sufficiently to permit the gate to clear the yoke 31, after which stress exerted on the flexible element 32 will be expended for the purpose of rocking the lever to produce swinging movement of the gate.

60 From the foregoing description, taken in connection with the drawings hereto annexed, the operation and advantages of this invention will be readily understood. It will be seen that a person approaching the 65 gate from either side, by seizing hold of

the depending end of one of the flexible elements 32 and pulling the same will first actuate the latch device to move the yoke 31 out of the path of the gate; a continued pull on the flexible element will then tilt the lever with which it is connected, causing one of the flexible elements 27, 27' to rock the arm 24 or 24' with which it is connected, thus swinging the gate from one side of the posts or uprights 15 to the other. When the gate is to be swung or moved from its open to its closed position, the operation is simply repeated, the tilting movement of the arm or arms 24, 24' being now utilized to swing the gate in the opposite direction. If the flexible element 32 is released before the gate reaches its closed position, the arms 29 of the latch device will gravitate in the direction of the sills, and the yoke 31 will be moved to an upwardly inclined position, as seen in Fig. 6; this, however, will not prevent the gate from reaching its closed position because the weight of the gate will tilt the latch device sufficiently to permit the passage thereof, the latch device being immediately afterward restored to its obstructing position with respect to the gate by the weight 30.

Having thus described the invention, what is claimed as new, is:—

1. A gate, tiltable arms supporting the gate for swinging movement, means for operating the arms to swing the gate from open to closed position, and vice versa, a latch device consisting of a rock shaft fulcrumed adjacent to the gate and having weighted arms extending in one direction, and a yoke extending in the opposite direction at an angle to said arms and positioned in the path of the heel portion of the gate, and means for rocking the latch device to move the yoke to a non-obstructing position with respect to the gate.

2. A gate, tiltable arms supporting the gate for swinging movement, means for operating the arms to swing the gate from open to closed position, and vice versa, a latch device consisting of a rock shaft fulcrumed adjacent to the gate and having weighted arms extending in one direction, and a yoke extending in the opposite direction at an angle to said arms and positioned in the path of the heel portion of the gate, and means for rocking the latch device to move the yoke to a non-obstructing position with respect to the gate, said means being operatively connected with the gate operating means so as to be operated simultaneously therewith.

3. In a device of the class described, a pair of sills, uprights rising therefrom and connected by a cross bar, operating levers fulcrumed on the cross bar and having inner and outer arms, a gate panel, a rock shaft mounted on the sills and extending between

the uprights, said rock shaft having an arm extending at one side of the gate panel and connected pivotally with the upper middle portion thereof, and another arm at the other 5 side of the gate panel, said arms having guide elements, a second rock shaft having an arm connected pivotally with the upper rear portion of the gate panel at one side thereof, a latch device comprising a rock shaft 10 journaled on the sills and having weighted arms extending in one direction and a yoke extending in the other direction and bent upward in the path of the heel portion of the gate, flexible elements connected with

the weighted arms of the latch device, 15 guided through the guide elements of the arms at opposite sides of the gate and through the guide elements on the outer arms of the levers and having pendent ends, and flexible elements connecting the inner 20 arms of the levers with the arms at the opposite sides of the gate having the guide elements.

In testimony whereof I affix my signature.
JOHN E. HENRIS.
